C. C. ABBOTT AND W. E. AND B. L. BASSETT.

FIRE ESCAPE.

APPLICATION FILED DEC. 9, 1920.

1,419,532.

Patented June 13, 1922.

UNITED STATES PATENT OFFICE.

CECIL C. ABBOTT, OF HARBOR SPRINGS, AND WILLARD EARL BASSETT AND BERT LESLIE BASSETT, OF DETROIT, MICHIGAN, ASSIGNEES OF ONE-FOURTH TO IRVIN L. BASSETT, OF DETROIT, MICHIGAN.

FIRE ESCAPE.

1,419,532.

Specification of Letters Patent. Patented June 13, 1922.

Application filed December 9, 1920. Serial No. 429,409.

To all whom it may concern:

Be it known that we, CECIL C. ABBOTT, residing at Harbor Springs, county of Emmet, and WILLARD EARL BASSETT and BERT L. BASSETT, residing at Detroit, county of Wayne, and State of Michigan, citizens of the United States, have invented certain new and useful Improvements in Fire Escapes, of which the following is a specification.

- 10 This invention relates to fire escapes and seeks to provide a device which will be simple and compact in the construction and arrangement of its parts and which may be readily anchored in a room and lowered 15 through a window to permit the occupant of the room to descend in safety to the ground. The invention also has for an object the provision of means for automatically governing the descent.

- 20 The invention is illustrated in the accompanying drawings, in which—

Figure 1 is a side elevation, partly broken away, and in section, of one embodiment of our invention;

- 25 Figure 2 is a similar view looking at the edge of the device;

Figure 3 is a transverse section on line 3—3 of Figure 1,

- In carrying out the invention, we employ 30 a casing which is preferably circular and comprises a circumferential wall 1 and side plates 2, as shown. Upon the circumferential wall, in the illustrated form of the invention, we rigidly secure an eye 3 which 35 may be engaged over a permanent hook or otherwise anchored to the wall of a room immediately adjacent a window. Upon the inner surface of the circular wall, we provide blocks or projections 4 at various points

- 40 to furnish supports for the operating mechanism presently set forth in detail. At a point diametrically opposite the anchoring eye 3, a slot or opening is provided in the circular wall 1 and through the said slot 45 or opening the lowering cable or flexible strap 5 passes. The inner end of this strap or cable is secured to a shaft 6 which is journaled in the side plates 2 of the casing, the cable or strap being wound about the 50 shaft, as shown and as will be understood. The free end of the strap or cable has permanently secured thereto a crosshead or bar 7 which is provided at its center with an

opening 8 through which a belt (not shown) may be inserted to be passed about the body 55 of the person who is to use the device and fastened so as to form a support. Hand holes 10 are formed in the bar 7 near the ends thereof so that the person descending by the use of the device may grasp the bar 60 and hold it against twisting and thereby minimize liability of the cable or strap binding in the opening through which it leaves the casing.

The casing is divided by a longitudinal 65 partition 11 which may conveniently be integral with the circular wall of the casing, the cable or strap being disposed within one of the chambers thereby produced and the shaft 6 extending transversely through both 70 chambers, as shown clearly in Figure 3. Upon the side of the partition more remote from the strap 5, is a boss 12 encircling the shaft 6 and having one end of the volute spring 13 secured thereto. The said spring 75 is wound about the boss 12 and is housed within and has its outer end secured to a drum 14 which is mounted loosely upon the shaft so as to be free to rotate about the same. Upon the annular wall of the drum 80 is a gear 15 which meshes with an elongated pinion 16 fixed upon a countershaft 17 which is journaled in the partition 11 and the side of the casing. The pinion 16 also meshes with an idler gear 18 disposed between the 85 drum and the adjacent side of the casing and carried by a stub shaft on the side of the casing. The idler in turn meshes with a pinion 19 on the shaft 6 and it will be readily seen that, by reason of this train of 90 gearing, the unwinding of the strap 5 will cause winding of the spring.

A worm shaft 20 is disposed longitudinally of the casing and is in mesh with the gear 15 as clearly shown. The worm shaft 95 20 is also equipped with a pinion 21, which, in turn, meshes with a second worm 22 formed upon a governor shaft 23, said shaft having a collar 24 secured thereto. To the said collar we secure leaf spring governor 100 arms 25, governor weights 26 being secured upon said arms at about their centers, as shown and as will be readily understood. A second collar 27 is secured to the arms 25 and is slidably mounted upon the governor 105 shaft, a brake disk 28 being carried by said

collar and adapted to bear upon a brake shoe 29 which is formed on the end of a floating lever 30 which is pivoted within the casing near the shoe. To the free end of the lever, 5 we secure the coiled tension springs 31 which extend in opposite directions from the lever and are attached in any convenient manner to the casing. These springs are of equal strength and, obviously, balance each other 10 so that they normally hold the brake shoe out of contact with but in position to be engaged by the governor brake disk.

It is thought the operation of the device will be readily understood. The brake shoe 15 29 is adjusted at the factory, the device being subjected to tests which will insure its safe descent when supporting a heavy person. When the device is not in use, the spring 13 will be unwound or loose and when 20 it becomes necessary to use the apparatus the descent of the escaping person will draw the cable or strap through and from the casing and exert a pull thereon which will set up rotation of the shaft 6, motion being thereby 25 transmitted through the gears 19, 18, 16 and 15 to rotate the arm in a direction opposed to the rotation of the shaft 6. The spring will consequently be wound and its tension 30 will act upon the strap 5 in opposition to the weight of the user. When the person reaches the ground and releases the device the spring will at once start to unwind and this action will cause the cable to be wound and withdrawn into the casing, the winding of the 35 cable or strap obviously causing the device to return to the room so that it may be used by another person. The rotation of the drum will be transmitted through the shown and described train of gearing to the governor 40 shaft and as the speed of said shaft increases the weights 26 will move outwardly under centrifugal action and thereby flex the springs 25 so that they will exert a pull upon the collar 27 and the brake disk 28 to

draw the brake disk against the brake shoe 45 29 in an obvious manner so that the frictional engagement between the disk and the shoe will retard the governor shaft and thereby check the descent.

It will be noted that the device is very 50 simple and compact so that it may be very easily moved from place to place and in both forms the descent will be automatically regulated, the maximum speed being determined by the adjustment at the factory before the 55 device is sent out.

Having thus described the invention, what is claimed as new is:

A portable fire escape comprising a casing provided with anchoring means, a partition within the casing, a shaft journaled in the ends of the casing and passing through the partition, a drum loose on said shaft at one side of the partition, a spring secured at its inner end to the partition adjacent 60 the shaft and secured at its outer end to the drum and wound within the drum, a flexible body-carrying device attached to and wound about the shaft at the opposite side of the partition and depending through the side of 70 the casing, a gear fixed on the shaft, a countershaft, an elongated gear on the countershaft, an idler mounted on the adjacent end of the casing between and meshing with said gears, a gear on the drum also meshing with 75 the elongated gear on the countershaft, a governor shaft driven by the gear on the drum, a speed governor mounted upon the governor shaft, a brake disk carried by the speed governor, and a brake shoe mounted 80 in the casing in position to be engaged by the brake disk.

In testimony whereof we affix our signatures.

CECIL C. ABBOTT.
